FIG. 6

INVENTOR.
GEORGE E. WHITE
BY *A. B. Barnard*
ATTORNEY

UNITED STATES PATENT OFFICE

GEORGE E. WHITE, OF SAN DIEGO, CALIFORNIA

BINDER RING

Application filed December 3, 1930. Serial No. 499,707.

My invention relates to permanent ring binders, more particularly to binders for sheaves of paper or the like, and the objects of my invention are:

5 First: to provide a device of this class which permanently binds sheaves of paper, such as a check book pad;

Second: to provide a binder ring which is particularly easy to install in a cover;

10 Third: to provide a binder ring which may be mounted entirely on the edge member of a cover, so that the leaves of paper carried thereby, when opened out, occupy a centered relation with the cover;

15 Fourth: to provide a device of this class which comprises a minimum number of parts, and most of these being duplicates in structure, thereby providing a device of this class which is particularly economical

20 of manufacture; and

Fifth: to provide on the whole a novelly constructed permanent ring binder which is simple of construction, durable, efficient in its action, and which will not readily deteriorate or get out of order.

25 With these and other objects in view as will appear hereinafter, my invention consists of certain novel features of construction, combination and arrangement of parts and portions as will be hereinafter described in detail and particularly set forth in the appended claims, reference being had to the accompanying drawing and to the characters of reference thereon, which form 30 a part of this application, in which:—

Figure 1 is a perspective view of my novel permanent ring binder in its open position; Fig. 2 is a sectional view thereof 40 when in its folded position, showing the binding rings in elevation; Fig. 3 is a perspective view of the retaining plate for the binding rings; Fig. 4 is an enlarged plan view of the binder ring; Fig. 5 is an enlarged side elevational view of one of the binder rings as it appears before installation in the cover; and Fig. 6 is an enlarged sectional view thereof through 6—6 of Fig. 5.

50 Similar characters of reference refer to

similar parts and portions throughout the several views of the drawing.

The binder ring is adapted to be mounted on a cover member C comprising a back leaf C1, a front leaf C2, and an edge member C3, which are connected together by suitable flexible webs C4, one on their outer sides and the other on their inner sides. This webbing is adapted to hinge the back, 55 front, and edge members together.

60 The binding ring 1 comprises a pair of complementary semi-circular members 2. Each semi-circular member is preferably formed from round stock and is reduced at one end, forming an offset projection 3. 65 This projection 3 is offset axially with respect to the axis through the center of the binding ring.

The two offset projections 3 overlap each other when the semi-circular portions 2 are in complementary relation, and are adapted to receive a pin 4 so as to hinge these two members together. The hinge formed by the projections 3 has practically the same 70 cross section as the two semi-circular portions, as shown best in Fig. 6.

75 The opposite ends of each semi-circular portion 2 is provided with a radially, outwardly extending arm 5, having a substantially rectangular cross section. When the two semi-circular portions are in complementary relation, the two arms 5 are adapted to fit against each other, as shown best in Figs. 2 and 5, thus the semi-circular members together form a split ring with the 80 arms 5 disposed adjacent or contiguous to the split in said ring.

85 Two or more binding rings are used with the covers C depending upon the size. In 90 addition to the binding rings, there is provided a retaining plate 6, which is flat and approximately the width of the edge member C3 of the cover. The retaining plate 6 is provided with two or more slots 7, one slot for each binding ring. Each slot 7 is adapted to receive the arms 5 of one pair of ring members when in contiguous relation, as shown in Figs. 2 and 5, thus preventing 95 the separation of the semi-circular portions 2.

The binding rings may be installed as follows: The plate 6 is positioned at the desired location on the edge member C3 and is used as a templet to form holes in the edge member for receiving the arms 5. The sheaves of paper P, shown by dotted lines in Fig. 2, are inserted over one or the other of the arms 5 when the binding rings are spread apart as shown in Fig. 10. 5. The arms 5 are then brought together, and the retaining ring is inserted through the proper slot and on through the edge member C3. Thereupon, the protruding portions of the arm 5 are bent over wherever by these portions function as elements of a split rivet as indicated by 5a in Fig. 2. This may be done before the outer flexible web C4 is placed on the cover, so that the protruding portions 5a may be pressed into 15 the edge members C and be covered and concealed by the outer flexible web C4.

It is obvious from the construction, as illustrated in the drawing and described in the foregoing specification, that I have provided a novelly constructed binding ring and cover as aimed at and set forth in the objects of the invention, and though I have shown and described a particular construction, combination and arrangement of parts 20 and portions, I do not wish to be limited to this particular construction, combination and arrangement, but desire to include in the scope of my invention the construction, combination and arrangement substantially 30 as set forth in the appended claims.

Having thus described my invention, what I claim as new and desire to secure by Letters Patent is:—

1. In a device of the class described, a 40 binder ring member comprising a pair of complementary semi-circular portions hinged together at their one ends and provided with radially extending arms at their opposite ends.
2. In a device of the class described, a 45 binder ring member comprising a pair of complementary semi-circular portions hinged together at their one ends and provided with radially extending arms at their opposite ends and a retaining means 50 arranged to receive said arms when they are closed together so as to hold said binder ring closed.
3. In a device of the class described, a 55 binder ring comprising a pair of complementary semi-circular portions hinged together at one end and provided with a pair of radially extending arms at their 60 opposite ends, a retaining means arranged to receive said arms when in closed relation so as to hold said binder ring closed, a cover, said arms adapted to extend through 65 said retaining means and a portion of said

means for securing said binder ring on said cover.

4. In a device of the class described, a 70 binder ring comprising a pair of complementary semi-circular members, hinge means at one end of each semi-circular member joining the same together, a radially extending arm at the opposite end of each semi-circular member, said binder ring arranged to receive a sheaf of perforated 75 paper by insertion over one of said arms and a retaining means for receiving said arms when close together for holding said binder ring in closed position.

5. In a device of the class described, a 80 binder ring comprising a pair of complementary semi-circular members, hinge means at one end of each of said semi-circular members joining the same together, a radially extending arm at the opposite end of each semi-circular member, said binder ring arranged to receive a sheaf of perforated 85 paper by insertion over one of said arms, a retaining means for receiving said arms when in closed relation so as to hold said binder ring in closed position, a cover for 90 said sheaf said arms adapted to extend through said retaining means and a portion of said cover and adapted to be bent down to form securing means for mounting said 95 binder ring on said cover.

In testimony whereof, I have hereunto set my hand at San Diego, California this 20th day of November, 1930.

GEORGE E. WHITE.
